S. GISSINGER.
Coal-Boring Bit.

No 72389

Patented Dec. 17, 1867.

Attest, { James McBride
James Johnston

Samuel Gissinger

United States Patent Office.

SAMUEL GISSINGER, OF MANCHESTER, PENNSYLVANIA.

Letters Patent No. 72,889, dated December 17, 1867.

IMPROVEMENT IN COAL-BORING BIT.

The Schedule referred to in these Letters Patent and making part of the same.

TO ALL WHOM IT MAY CONCERN:

Be it known that I, SAMUEL GISSINGER, of the city and county of Allegheny, in the State of Pennsylvania, have invented a new and useful Improvement in "Boring-Bits" for Coal-Mining Machines; and I do hereby declare the following to be a full and exact description thereof, reference being had to the accompanying drawings, and to the letters and figures of reference marked thereon.

The nature of my invention consists in providing the boring-bits of coal-mining machines with an entering and centring-point, scoring and cutting-points, and a guide, and so arranging the bits on the boring-shafts of the mining-machine that they will cut out a gap or space between the bits, and thereby forming one "bearing-in" cavity.

To enable others skilled in the art to make and use my invention, I will proceed to describe its construction and operation.

In the accompanying drawings, which form part of my specification, *x* represents the frame for the boring-shafts 1, 2, and 3, which may be revolved and moved forward by any known mechanism. To the forward ends of the shafts 1, 2, and 3, I secure the boring-bits *A*, which are provided with entering or centring-points *B*, cutting and scoring-points *e* and *f*. The portion *d* of the bit between the cutting-points *f* and *e* acts as a guide for the bit, causing it to cut on a true line with the plane of its shaft, thereby preventing all undue strain on the bit-shaft. The boring-bits are made from flat bars of steel, and are arranged alternately on the shafts 1, 2, and 3, in the manner shown in the drawings.

The operation of my invention is as follows: Motion is imparted to the shafts 1, 2, and 3, so that each shaft moves at the same speed. The shafts are made to move forward by any known mechanism. The points *B* cut their way into the coal, and will steady or act as a centre-point for the cutters *f*, which cut, score, or chip out their way into the coal, and the points *B* and *f*, and the part marked *d*, will act as a centre or guide for the cutting-points *e*, which will cut, score, or chip their way into the coal.

By making the bits in the form represented in the drawings, and arranging them on the shafts in the manner described and represented, the bits will score or chip one continuous "bearing-in" cavity for "breaking down the coal," said cavity being always made true and on the line desired.

The effect produced by my improvement in "bits" for coal-mining which distinguishes them from other "boring-bits" of such machines, consists in chipping or scoring out of the coal, instead of a drilling process. This chipping or scoring process is produced by the recesses marked *s*. The points *B*, *e*, and *f*, cut their way into the coal, and that portion of the coal which comes into the recesses *s* is broken or chipped off and thrown out by the revolving of the "bits."

The form of my improved "bits" will in every case prevent the tendency of the "bits" from travelling out of a direct line. It is a fact well known to those skilled in the art of mining coal, that one of the great obstacles in "bearing-in" or undermining is the difference in the formations found in the bed of coal. At one point it is hard, at other points it is soft, and this difference in the bed of coal causes the ordinary "boring-bits" to travel out of a direct line. I overcome these difficulties and obstacles by the use of the "boring-bits" herein described and represented.

Having thus described the nature, construction, and operation of my improvement, what I claim as of my invention, is—

The bit or cutter *A*, provided with the entering-point *B*, scoring and cutting-points *e* and *f*, and guide *d*, substantially as herein described, and for the purposes set forth.

SAMUEL GISSINGER.
